Attorney.

UNITED STATES PATENT OFFICE.

SIMON CHARLES MENDELSON, OF JOHANNESBURG, TRANSVAAL, SOUTH AFRICA.

DESIGN FOR A MAT-HOLDER.

59,503.

Specification for Design.

Patented Oct. 25, 1921.

Application filed November 2, 1920. Serial No. 421,423. Term of patent 7 years.

To all whom it may concern:

Be it known that I, SIMON CHARLES MENDELSON, a British subject, residing at 34^a Eloff street, Johannesburg, Transvaal, Province of the Union of South Africa, have invented a new, original, and ornamental Design for a Mat-Holder, of which the following is a specification, reference being had to the accompanying drawing, forming part thereof.

The drawing is a perspective view of a mat holder, showing my design.

I claim:

The ornamental design for a mat holder, as shown.

SIMON CHARLES MENDELSON.
